LIQUID REFRESHMENT DISPENSING CABINET

Melvin H. Boldt, Glenview, and Thurber H. Morrison, Evanston, Ill., assignors to Canteen Corporation, Chicago, Ill.

Filed Mar. 5, 1975, Ser. No. 555,545

Term of patent 14 years

Int. Cl. D6—04; D20—01
U.S. Cl. D94—3 A

FIG. 1

FIG. 2

FIG. 1 is an enlarged perspective view of a liquid refreshment dispensing cabinet showing our new design;

FIG. 2 is a side elevational view thereof;

FIG. 3 is a front elevational view thereof.

The rear which is not shown is flat and unornamented.

We claim:

The ornamental design of a liquid refreshment dispensing cabinet, substantially as shown and described.
